UNITED STATES PATENT OFFICE.

JOHN M. ROTH, OF PHILADELPHIA, PENNSYLVANIA.

DESIGN FOR A TAG-FASTENER.

SPECIFICATION forming part of Design No. 35,338, dated November 26, 1901.

Application filed October 21, 1901. Serial No. 79,490. Term of patent 7 years.

To all whom it may concern:

Be it known that I, JOHN M. ROTH, a citizen of the United States, residing at Philadelphia, in the county of Philadelphia and State of Pennsylvania, have invented and produced a certain new and original Design for Tag-Fasteners; and I do declare the following to be a full, clear, and exact description of the invention, such as will enable others skilled in the art to which it appertains to make and use the same.

The invention relates to a new and original design for a tag-fastener; and it consists of the design shown in the accompanying drawings, in which—

Figure 1 is a side view, Fig. 2 is a top plan view, and Fig. 3 is an end view.

The leading feature of the design comprises

the longitudinal part 1, having a bow 2 at one end, terminating in a forwardly-projecting part 3, overlying the part 1, and formed with a curved point 4, which lies over a horizontal doubled part 5, terminating at the forward end of the part 1 and extending on opposite sides thereof.

25

What I claim is—

The design for a tag-fastener, as herein shown and described.

In testimony whereof I have hereunto set my hand in presence of two subscribing witnesses.

JOHN M. ROTH.
